Specification for Design.

Patented Aug. 11, 1914.

Application filed April 16, 1914. Serial No. 832,392. Term of patent 14 years.

To all whom it may concern:

Be it known that I, HARRY E. POTTEIGER, a citizen of the United States, residing at Sinking Spring, in the county of Berks and State of Pennsylvania, have invented a new, original, and ornamental Design for Bottles, of which the following is a specification, reference being had to the accompanying drawing, forming part thereof.

I claim:

The ornamental design for a bottle as shown.

In testimony whereof I affix my signature in presence of two witnesses.

HARRY E. POTTEIGER.

Witnesses:

ADAM L. OTTERBEIN,
